(57) **CLAIM**

The ornamental design for a traction member for a vehicle
recovery ladder, as shown and described.

DESCRIPTION

FIG. 1 is a top plan view of a traction member for a vehicle
recovery ladder in accordance with our new design;

FIG. 2 is a bottom plan view of the traction member for a
vehicle recovery ladder shown in FIG. 1;

FIG. 3 is a front elevation view of the traction member for
a vehicle recovery ladder shown in FIG. 1;

FIG. 4 is a rear elevation view of the traction member for a
vehicle recovery ladder shown in FIG. 1;

FIG. 5 is a side elevation view of the traction member for a
vehicle recovery ladder shown in FIG. 1, taken from the
right side of FIG. 1;

FIG. 6 is a side elevation view of the traction member for a
vehicle recovery ladder shown in FIG. 1, taken from the left
side of FIG. 1;

FIG. 7 is a perspective view of the traction member for a
vehicle recovery ladder shown in FIG. 1, taken from the top,
front, and right side of FIG. 1; and,

FIG. 8 is a perspective view of the traction member for a
vehicle recovery ladder shown in FIG. 1, taken from the
bottom, front, and right side of FIG. 1.

The broken lines illustrate portions of the traction member
for a vehicle recovery ladder that form no part of the claimed
design.

1 Claim, 8 Drawing Sheets

Related U.S. Application Data

is a continuation-in-part of application No. PCT/AU2016/051051, filed on Nov. 4, 2016.
